UNITED STATES PATENT OFFICE.

VALENTINE J. WATRAL, OF NEW YORK, N. Y.

DESIGN FOR A LAMP PEDESTAL.

Application filed May 13, 1926. Serial No. 17,681. Term of patent 3½ years.

To all whom it may concern:

Be it known that I, VALENTINE J. WATRAL, a citizen of Czechoslovakia, and a resident of New York, in the borough of Queens, county of Queens, State of New York, United States of America, have invented a new, original, and ornamental Design for a Lamp Pedestal, of which the following is a specification, reference being had to the accompanying drawing, forming part thereof.

The drawing is a perspective view of a lamp pedestal showing my new design.

I claim:

The ornamental design for a lamp pedestal, substantially as shown.

VALENTINE J. WATRAL.
